PRINTING PLATE

Walter T. Gollwitzer, Cleveland, Ohio, assignor,
by mesne assignments, to Addressograph-Mul-
tigraph Corporation, Cleveland, Ohio, a corpo-
ration of Delaware

Application April 29, 1935, Serial No. 18,796

4 Claims. (Cl. 101—369)

In my prior application No. 612,955, filed May 23, 1932, I have shown an address plate comprising a frame having means for engaging the longitudinal edges of an embossed printing plate 5 and having flat spring tongues carrying raised abutments to coact with the ends of the printing plate. The printing plate there shown has a notch in the end with parallel side edges to form a close engagement with the side edges of a portion of the raised abutment which connects 10 a lip thereon with the body of the spring tongue.

Now, I have found that under certain circumstances the parallel-sided notches in the plate cease to be effective and the plate when embossed is likely to become too long to seat between the raised abutments on the spring tongues. Also, the notch sometimes became too narrow at the entrance for the connecting portion of the abutment to enter the notch. I find 15 that this action is caused by the distortion of the metal plate due to the embossing of characters comparatively near the end thereof.

In my prior application No. 687,616, filed August 31, 1933, I have shown an address plate 25 provided with a notch having its base (that is the boundary most distant from the end and parallel therewith) of a length substantially equal to the corresponding dimension of the connecting portion between the abutment and spring 30 tongue of the frame, and having side walls which diverge slightly from such base to the end of the plate. The result of such a notch is such that, when embossed, the plate material adjacent the ends is forced into the notch, so that 35 the ultimate side walls of the notch are substantially parallel or at least will not choke the entrance to the notch. Such a notched plate also either does away with the longitudinal protrusion of the plate, or so reduces it as to render 40 it negligible.

I have found, however, that different materials and metals react differently to the embossing action and that even different lots of supposedly the same material react differently. For 45 instance, some materials expand farther than others under the embossing action and hence, in some instances, may so restrict the distance across the end of the notch as to prevent the connecting portion of the abutment on the frame 50 from entering the notch. Likewise, if the distance across the end of the notch is such as to insure entrance of the connecting portions of the plate abutments for substantially all types of embossable materials, the engagement of the side 55 walls of the notch and the ends of the plate

adjacent the side walls of the notch with the abutment is lost, unless the metal has definite physical characteristics, and the aligning and locating advantages of the notch and abutment are lost. 5

As a result of experimentation and trial, I have found that I can overcome the disadvantages described in connection with either a parallel walled or outwardly flaring notch by flaring the notch inwardly, that is, by making the distance across the notch at the end of the plate less than the length of the boundary of the notch most distant from the end of the plate and parallel therewith. The result will be that, when the plate is embossed, the end of the plate adjacent the notch will be unaffected by the embossing. Hence, by making the distance across the notch at the end of the plate such that it will advantageously coact with the abutment of the frame, and by increasing the distance between 20 the side walls of the notch as they recede inwardly from the end of the plate, I secure the full advantages of the coacting notch and frame abutment, regardless of the specific characteristics of the material or metal used. This type of 25 notch either does away with the longitudinal and lateral protrusions of the plate, or at least eliminates such extrusions where the end of the plate coacts with the abutment of the frames. 30

My invention in its broad aspect may be said 30 to comprise a plate adapted for mounting on a frame and having in its end a notch of a pre-determined width and which plate is further provided, intermediate the entrance of the notch and printing character area of the plate, with means 35 to prevent the effecting of the contour of the plate at the entrance to the notch by the flow of metal, consequent upon the embossing of the plate. Such means preferably extends at either side of the longitudinal axis of the notch a 40 greater distance than do the corners formed by the entrance of the notch. Such above-mentioned means may comprise a cut-out portion of the plate intermediate the entrance of the notch and the printing character area of the plate, the 45 distance between the ends of such cut-out portion and the longitudinal margins of the plate being greater than the distance between the corners of the entrance of the notch and respective margins of the plate. The cut-out portion may 50 be formed integral with the notch or independent thereof, as desired.

The specific embodiment of the invention illustrated in the drawing comprises a printing plate adapted for mounting on a frame and hav- 55

ing in its end a notch with its side edges flaring inwardly sufficiently to avoid the troublesome distortion while maintaining the width of the notch at the edge of the plate constant, to 5 permit accurate holding and positioning of the plate by the frame-portion occupying the notch. The invention is hereinafter more fully explained in connection with the drawing.

In the drawing Fig. 1 is a plan of an address 10 plate comprising a frame carrying an index card and one of my printing plates; Fig. 2 is a plan of a portion of the frame and printing plate with the latter partially removed; Fig. 3 is a sectional perspective of an end portion of the frame and 15 a printing plate mounted thereon; Fig. 4 is a perspective of an end portion of the frame without the printing plate; Fig. 5 is a cross-section through a portion of the frame and the printing 20 plate mounted thereon, as indicated by the line 5—5 on Fig. 3; Fig. 6 is a plan of a portion of the plate near one end before it is embossed; Fig. 7 is a plan of the same after it is embossed; Fig. 8 is a plan of a parallel sided notched plate 25 before embossing, and Fig. 9 the same after embossing; Figs. 10 and 11 are fragmentary vertical sectional views through the embossing dies illustrating the action thereof on the printing plate, each view being a section on the correspondingly numbered line on the other view.

30 As shown in Figs. 1 to 4, 10 indicates the frame of the address plate, 40 the printing plate mounted thereon, and 30 the index card which may also be mounted on the address plate. As shown, the address plate is a sheet-metal member having 35 a curled over lower edge 11, stamped-up downwardly projecting ears 12 to form a slideway for the printing plate, and a curled-over upper edge 13 and stamped-up upwardly projecting ears 14 to form a pocket in which the index card 30 may 40 be mounted.

The lower portion of the frame 10 is formed with spring tongues 15 cut out of the body of the plate, each having near one end a raised lip 16 presenting abrupt shoulders 17 to engage the 45 end of the printing plate, and a gradually inclined central portion 18 connecting the raised lip with the body of the tongue, and adapted to occupy the notch of the plate. The inclined central portion 18 provides abrupt shoulders 20 to engage the side walls of the notches in the ends of the plate and thereby accurately locate the plate on the frame. This permits the use 25 of a loose fit between the plate and its guideways 11 and 12 to enable the plate to be easily inserted 30 on the frame. The raised portion 16 is also connected with the body of the tongue 15 by extreme portions 19 set back beyond the abrupt shoulders 17.

The frame above described is claimed in my 35 copending application referred to, and is here set out in order that the action of the printing plate may be better understood.

The printing plate 40 is of such a size that it 40 may be readily slid into place in the shallow 65 pocket provided by the curled-over edge 11 and the overhanging ears 12. If desired, the upper and lower edges of this plate may be scalloped as shown, which has been found to aid in the ready insertion of the plate into the pocket. The 70 plate has in each end a central notch 41, which is designed to receive the connecting portion 18 of the spring tongue when the end of the plate abuts the abrupt shoulders 17. The depth of this notch from the end of the plate is at least as great as 75 the longitudinal dimension of the connecting por-

tion 18 of the tongue, so that the end of the plate on opposite sides of the notch may freely abut the shoulders 17. The width of the notch at the edge of the plate is preferably substantially the same as that of the connection portion 18, while the distance between the side walls of the notch increases from the edge of the plate inwardly as shown in Fig. 6. For convenience, such notch may be termed a dovetailed notch. However, it is to be understood that I use the term "dovetail" in a broad sense to include any notch wherein the entrance to the notch is restricted relative to another dimension of the notch parallel with the entrance and inwardly therefrom.

When such a plate as illustrated in Fig. 8 is submitted to the action of an embossing machine to print characters thereon in a region close to the notch, they distort the metal of the plate, and if there is no place for this metal to go, the 20 distortion will cause the plate to protrude at the end, or the notch to become narrowed at its opening, each of which conditions is troublesome in the mounting of the plate on the frame. With the dovetailed notch, however, the embossing 25 action does not affect the protruding corners 42 of the plate. Therefore the plate will not bind on the connecting portion 18 of the frame tongue, nor will it protrude troublesome beyond the 30 normal end of the plate to bind on the shoulders 17 of the frame tongue.

I have illustrated the action of the embossing operation in Fig. 9 on a parallel walled notch where the pressing action of the dies in making the characters 22 causes the side walls of the 35 notch 41a to approach each other restricting the entrance to the notch and lengthening the plate adjacent the edges of the notch.

The distortion adjacent the end of the plate, 40 illustrated in Figs. 8 and 9, results from the spreading or flowing of the metal of the plate, due to the pressure of the embossing dies. As illustrated, for instance, in Figs. 10 and 11, the two dies 50 act on the plate 40 to form first a raised 45 seat on the plate, designated 24, and then the character 22, still further raised from the seat. The result is the material of the plate is considerably reduced in thickness and changed in 50 form by the pressure of the dies, which causes the metal of the plate to flow in the direction of the plane of the plate. Some of this flow is toward the end of the plate and is sufficiently resisted by the plate except adjacent the notch, but with the dovetailed notch the flow of the metal is interrupted by the widened base 43 of the notch. The lateral flow of the metal seems to act in a curvilinear path as indicated by the curved lines 44 55 on Fig. 7, and does not affect the mouth of the notch. Any slight flow effect acts only to decrease 60 the width of the notch at its base and therefore may be disregarded for all practical purposes.

From the foregoing it is readily apparent that my improved plate is provided with notches which 65 prevent both longitudinal and transverse movement of the plate relative to the frame by intimate engagement of the corners at the entrance to the notch of the plate with shoulders or abutments formed on the frame. The arrangement 70 of the notch is such as to provide an entrance of a predetermined width at the edge of the plate, which width is unaffected by the action of the character embossing dies, and is not restricted by the flow of metal during the embossing action; 75

nor does it depend upon such flow for its final dimension.

It is desirable not to give a greater flare to the notch than necessary to prevent the most severe distortion of the plate at the notch entrance. My experience has demonstrated that it is preferable to make the flare or slope of the sidewalls of the notch about 30° as shown in Fig. 6 of the drawing, as this angle effectively eliminates the distortion of the abutment engaging surfaces of the plate.

While I do not wish to limit myself to particular dimensions, I have found that with the frame of the form shown in Fig. 4, having the connecting portion 18 of a longitudinal extent of .040 inch, and of a width (measured parallel with the end of the plate) of .055 inch, I can obtain excellent results in a plate having a notch of a depth of .045 inch and a width which at the bottom is .080 inch and which at the top (that is at the end edge of the plate or entrance to the notch) is .055 inch. With such a holder and such a plate, the end of the plate firmly abuts the shoulders 17 on opposite sides of the notch, and the side walls of the notch at the entrance of the notch substantially engage the edges 20 of the connecting portion 18. This is sufficient to hold the plate located in the desired position without further bearing of the sides of the notch against the connection 18.

It will be seen that I have provided a plate which is substantially universal in action and is adapted to be effectively mounted on a holder or

frame of the character described, irrespective of the amount of embossing on the plate, or the type or specific physical characteristics of the metal used for forming the plate.

I claim:

1. A relatively long and narrow blank for a printing plate adapted to be mounted on a frame, said blank having, in at least one end, a comparatively narrow notch with its sides flaring toward the interior of the plate. 10

2. A substantially rectangular blank of sheet material adapted to be embossed and having a straight end interrupted in its mid-region by a comparatively narrow notch of trapezoidal form with the shorter of its parallel sides at the entrance to the notch. 15

3. A comparatively long and narrow blank for a printing plate having an area receptive for embossed printing characters and having a notch in one end thereof and provided with a cut-out portion intermediate the entrance to the notch and the printing character area, the width of the opening at said cut-out portion being greater than the width of the mouth of the notch. 20

4. A comparatively long and narrow blank for a printing plate adapted to have printing characters embossed thereon and having comparatively narrow notches located in central regions at each end of the blank, said notches being wider at their base than at the entrance to the notch, and the marginal ends of the plate being straight, interrupted only by the entrance to the notch. 25 30

WALTER T. GOLLWITZER.
